UNITED STATES PATENT OFFICE.

ABRAHAM LUDWIG, OF DETROIT, MICHIGAN.

DESIGN FOR A BATHROOM FIXTURE.

Application filed May 23, 1929. Serial No. 31,347. Term of patent 14 years.

To all whom it may concern:

Be it known that I, ABRAHAM LUDWIG, a citizen of Poland, residing at Detroit, in the county of Wayne and State of Michigan, have invented a new, original, and ornamental Design for Bathroom Fixtures, of which the following is a specification, reference being had to the accompanying drawing, forming part thereof.

I claim:—

The ornamental design for a bathroom fixture, as shown.

ABRAHAM LUDWIG.
